UNITED STATES PATENT OFFICE.

ARTHUR E. TRUESDELL, OF RUTLAND, VERMONT, AND LEWIS F. PHILLIPS, OF WEST STOCKBRIDGE, MASSACHUSETTS.

ROTARY KILN.

1,350,750.

Specification of Letters Patent. Patented Aug. 24, 1920.

Application filed October 20, 1916. Serial No. 126,789.

To all whom it may concern:

Be it known that we, ARTHUR E. TRUESDELL and LEWIS F. PHILLIPS, citizens of the United States, residing, respectively, at Rutland, county of Rutland, State of Vermont, and West Stockbridge, county of Berkshire, State of Massachusetts, have invented an Improvement in Rotary Kilns, of which the following description, in connection with the accompanying drawing, is a specification, like characters on the drawing representing like parts.

This invention relates to rotary kilns and particularly to kilns of this type which are designed for burning lime. Rotary lime kilns as now commonly made comprise a single cylindrical burning chamber which is set at a slight inclination and is mounted upon two separated bearings, means to feed the unburned lime into the upper end of said chamber, and means to introduce combustible gases into the lower end of the chamber. The rotation of the cylindrical chamber causes the lime to gravitate gradually toward the lower end, and during its movement through the chamber, the burning operation takes place, the products of combustion being delivered to a stack connected to the upper end of the chamber.

It is a desideratum to make the chamber as long as possible, so that the lime will have a better chance to become thoroughly burned while it is traveling from one end to the other of the rotary kiln, but there is a limit to the length which the cylindrical chamber of a rotary kiln can be made practically, for if said chamber has too great a length, it will not be strong or rigid enough to be supported properly on two bearings only, and it has been found in practice to be impracticable to use more than two bearings because of the difficulty in keeping the bearings in alinement. Moreover, if a rotary kiln is made of too great a length, there will be no burning or calcining action in the upper end of the kiln because as the combustible gases pass upwardly through the kiln, they become consumed and commingled with CO₂ gas which is delivered from the burning lime, and in a long kiln there will be such an accumulation of the CO₂ gas at the upper end of the kiln as to prevent any burning action. Consequently, heretofore, it has not been deemed practicable to make a rotary kiln of a greater length than about one hundred and twenty feet.

One of the objects of our invention is to provide a novel construction by which the length of a rotary kiln can be increased to a considerable extent without involving any of the disadvantageous features above referred to.

We propose to do this by making the kiln in two sections arranged in tandem, each section being independently supported on two bearings, and said sections being provided with a joint between them which permits the limestone to pass freely from the upper section to the lower section, while permitting sufficient free play between the sections so that they will rotate freely, even though they are not entirely in alinement. We also propose to provide a novel means by which an added volume of air, preferably heated air, can be introduced into the kiln at some point between its ends, this added volume of air (which for convenience we will hereinafter term "secondary air") furnishing added oxygen to the gases in the kiln so as to counteract the effect of the CO₂ gas and provide for continuing combustion through the entire length of the elongated kiln.

In order to give an understanding of our invention, we have illustrated in the drawings a selected embodiment thereof which will now be described, after which the novel features will be pointed out in the appended claims.

Figure 1 shows a kiln embodying our invention in vertical section:

Fig. 2 is a section on the line 2--2, Fig. 1;

Fig. 3 is a section on the line 3--3, Fig. 1.

Our improved kiln comprises the upper section 1 and the lower section 2, each in the form of an elongated cylindrical chamber. The upper section 1 is rotatably mounted upon the two bearings 3 and 4 and is provided with the gear 5, as usual, by which it may be rotated. The lower section 2 is mounted on two bearings 6 and 7 which are independent from the bearings 3 and 4, and it is provided with the gear 8 by which it may be rotated. Preferably the gears 8 and 5 will be driven from the same source of power so that the two kiln sections 1 and 2 will rotate in unison. The upper end of the upper kiln section 1 communicates with the usual dust chamber 9 having the stack 10 leading therefrom and the unburned material is fed to the kiln section 1 through a feeding hopper or chute 11, as usual. The

lower end of the upper section 1 extends into the upper end of the lower section 2 so that the material which passes through the upper section is delivered into the lower section.

The lower end of the lower kiln section 2 is connected to a gas producer 12 of any suitable or usual construction which produces combustible gases that are delivered to the kiln. The burnt material is discharged from the kiln into an inclined rotatable cylindrical chamber 13, as usual in rotary kilns of this type.

By making the kiln in two sections 1 and 2 and providing independent bearings for each section, a longer kiln can be made than would be possible if the kiln was in the form of a single chamber only. The upper kiln section 1 can be made practically as long as it is possible to make an ordinary kiln, and the lower kiln section 2 can be made as long as desirable, thus adding to the total length of the kiln. Since these kiln sections are independent from each other and are sustained in independent bearings, and since the joint between the upper end of the kiln section 2 and the lower end of the kiln section 1 allows of a certain amount of play, the operation of the kiln will not be affected at all, even though the two kiln sections are not in absolute axial alignment. By thus making the kiln in two sections, it is possible to build a practical kiln of considerably increased length. The increase in length adds to the time which it takes for the material to travel through the kiln, and thus gives added time for the burning operation.

Where the length of the kiln is thus increased, it is desirable that an added quantity of air should be introduced into the kiln at some point between its ends so as to support combustion at the upper end of the kiln. We accomplish this herein by providing the lower kiln section 2 with a jacket 14 which forms with said lower kiln section a chamber 15. The lower end of the chamber 15 is open to the atmosphere at 16. The jacket 14 extends beyond the upper end of the lower kiln section 2 and is formed with the inturned flange 17 which engages the upper kiln section 1. A space 18 is provided between the upper and lower sections which affords communication between the chamber 15 and the interior of the kiln. With this construction air will enter the chamber 15 at 16 and will become heated therein by contact with the walls of the kiln section 2, and the heated air will be delivered through the space 18 into the kiln at a point between its ends. This added air (which we have termed secondary air because the air which is admitted with the combustible gases at the lower end of the kiln section 2 constitutes the primary air) supports combustion in the

upper end of the kiln so that notwithstanding the fact that considerable CO₂ gas is given off from the burning lime there will be a sufficient supply of oxygen in the upper end of the kiln to insure the complete combustion of all the combustible gas produced at the lower end of the kiln. The full benefit of all the combustible gas is thus obtained and burning of the lime is accomplished without any combustible gas being wasted. By means of the increased or lengthened burning area a more uniform product can be produced and a larger quantity of material can be burned in a given time than is possible with the rotary kilns as heretofore constructed.

Having fully described our invention, what we claim as new and desire to secure by Letters Patent is:

1. In a rotary kiln, the combination with a rotatable cylindrical burning chamber, of means to deliver combustible gas and primary air to the lower end of said chamber, a jacket surrounding a portion of said chamber and open at one end to the atmosphere, and means constituting a communication between the other end of said jacket and the burning chamber at a point intermediate of its ends whereby heated secondary air will be delivered to said burning chamber.

2. In a rotary kiln, the combination with upper and lower kiln sections, each independently supported for rotative movement, the lower end of the upper kiln section and the upper end of the lower kiln section being separated to form an air inlet, and means to supply heated secondary air to said inlet.

3. In a rotary kiln, the combination with upper and lower kiln sections arranged in alignment with each other, and each independently supported for rotative movement, of means to deliver combustible gas to the lower end of the lower section and a jacket surrounding the lower section and open to the atmosphere, said jacket communicating with the kiln at the upper end of the lower section whereby heated air will be delivered from the jacket to the kiln intermediate of its ends.

4. In a rotary kiln, the combination with upper and lower kiln sections, each independently supported for rotative movement and arranged to provide a space between the lower end of the upper kiln section and the upper end of the lower kiln section, and a jacket surrounding the lower kiln section and communicating with said space whereby heated secondary air is furnished to the kiln between said sections.

In testimony whereof we have signed our names to this specification.

ARTHUR E. TRUESDELL.
LEWIS F. PHILLIPS.
